UNITED STATES PATENT OFFICE

93,657

DESIGN FOR A HEATER

Rudolph Hoffman, Rocky River, Ohio, assignor
to American Stove Company, St. Louis, Mo., a
corporation of New Jersey

Application August 16, 1934, Serial No. 52,971

Term of patent 14 years

To all whom it may concern:

Be it known that I, RUDOLPH HOFFMAN, a citizen of the United States, residing at Rocky River, county of Cuyahoga, and State of Ohio, have invented a new, original, and ornamental Design for Heaters, of which the following is a specification, reference being had therein to the accompanying drawing.

Figure 1 is a perspective view of a heater.

Figure 2 is an enlarged plan or face view of a part of the ornamentation shown in Fig. 1.

It will be understood that the grille work passes around substantially the whole top and lower edges of the heater, while it is shown covering only part of the way around the heater in Figure 1.

I claim:

The ornamental design for a heater, as shown and described.

In testimony whereof, I hereto affix my signature.

RUDOLPH HOFFMAN.
